UNITED STATES PATENT OFFICE

2,612,013

APPARATUS FOR GRINDING CRANKSHAFTS

Alfred Loader, Millbury, and Michael S. Koylowski, Worcester, Mass.

Application September 13, 1951, Serial No. 246,486

3 Claims. (Cl. 51—237)

1

This invention relates to method and apparatus for grinding the bearings in crankshafts, and the principal object of the invention resides in the provision of a much faster and easier method of aligning the crankshaft in a machine for rotating the same on its axis so that a grinding wheel may be moved transversely with respect thereto to grind the bearings, this resulting in saving of time and effort on the part of the operator and increased accuracy as to the work done.

Another object of the invention resides in the provision of a flanged cylindrical hollow member having a driving dog thereon and receiving the usual small end of a crankshaft, the flange of this member being received within the area of a rim on a circular plate-like jig or the like in radially adjustable relation thereto, these two members being bolted together in adjustable relation and the plate having means for arranging the same on the center of the head stock of a lathe, in combination with a more or less similar plate-like jig to be arranged on the center of the tail stock and having a rim receiving the flange at the opposite end of the crankshaft, this plate being directly bolted to the flange in adjustable relation therewith in a radial direction relative to the lathe centers and both plates having means for adjusting the hollow cylindrical member and the shaft flange respectively, to the end that the shaft ends are easily and quickly radially adjusted substantially micrometrically and at the same time the shaft is rotated on the axis thereof as by the dog on the cylindrical member above described, the plates described serving to hold and center the shaft.

Other objects and advantages of the invention will appear hereinafter.

Reference is to be had to the accompanying drawings, in which

Fig. 1 is a view in elevation with parts in section showing the set-up of the new device with respect to the head stock of a lathe;

Fig. 2 is a similar view showing the set-up with respect to the tail stock;

Fig. 3 is an enlarged view in front elevation of the hollow cylindrical member;

Fig. 4 is a front view on enlarged scale of the plate of Fig. 2, looking in the direction of arrow 4 in Fig. 2; and

Fig. 5 is a view in elevation on enlarged scale of the plate and associated members of Fig. 1.

In carrying out the present invention, the same is to be applied to a crankshaft 10 having a flange at one end at 12 and a bearing or gear

10 end as the case may be at 14. The bearings for the crankshaft, as for example 16, are to be ground as by a wheel 18 and the crankshaft is to be rotated about a true center, so that the wheel 18 may be brought in to grind the bearing with the least possible cut and vibration to result in a crankshaft having all bearings ground on an exact axis.

15 A hollow cylindrical member 20 having a means such as a set-screw 22 radially arranged therein receives the end 14 of the crankshaft in closely fitting condition, with the means 22 securing the same non-rotatably therein. The cylindrical member 20 is provided with a flange 24 which is circular as shown in Fig. 3 and this flange is provided with a series of threaded bolt-receiving holes 26 which extend parallel to the axis of the member. This member also is provided with a driving dog 28 for cooperation with a driver 30 on the head stock 32 of a lathe which has a center 34 and a tail stock center 36.

20 In conjunction with the cylindrical member 20, there is provided a plate-like jig 38 which has a flange or rim 40. In this rim there are provided a series of adjusting means 42 arranged radially, see particularly Fig. 5. These may take the form of screws which engage the periphery of the flange 24 of the cylindrical member 20, so that the latter may be adjusted where desired radially relative to the lathe centers. When adjusted as desired, the bolts 44, arranged in slots, are tightened to rigidly secure plate 38 to the cylindrical member 20 in adjusted position.

25 The flange 12 is received in a plate 46 which also has a rim or flange 48 receiving the flange 12 of the shaft, the latter being drilled and tapped for the reception of bolts 50, in radial slots 52, and radial screws or other means 54 are provided similarly to those at 42 for radial adjustment 30 of the flanged end of the crankshaft relative to the lathe centers. All of the bolts work in respective slots to accomplish the adjustment.

35 With the set-up disclosed, the end 14 of the crankshaft is inserted in the cylindrical member 45 which may or may not already be lightly secured to plate 38, and the flange 12 is inserted in the other plate 46. This assembly then being placed on the lathe centers, the shaft is easily centered on a true axis with respect to the lathe centers 50 for the grinding operation above described, but the center holes for the lathe centers in the shaft itself are not used, so that a new, more accurate crankshaft axis is produced, particularly for re-finished work.

55 Having thus described our invention and the

advantages thereof, we do not wish to be limited to the details herein disclosed, otherwise than as set forth in the claims, but what we claim is:

1. Apparatus for centering and grinding a crankshaft having a flange at one end thereof comprising a hollow flanged cylindrical member into which the end of the shaft fits, means to secure the shaft end in the member, a plate, a rim on the plate, the flange of the cylindrical member being received in the rimmed area of the plate, means adjustably but firmly securing the cylindrical member flange to the plate, means to adjust the cylindrical member flange radially, a second plate, a rim thereon, the shaft flange being received therein, releasable means to adjustably secure the shaft flange to the second plate, means to adjust the shaft flange radially on the second plate, and means to center the plates on the centers of a lathe.

2. The apparatus of claim 1 including a radial driving dog on the hollow cylindrical member.

3. Apparatus of the class described for centering and grinding a flanged crankshaft comprising a pair of plate-like jigs each having an edge rim and a lathe center receiving notch, radial adjusting screws in the rims thereof, and bolts working

in radial slots and being axially parallel, a hollow cylindrical member, a flange thereon, a dog on the member, means to receive the bolts of one jig in the member, the bolts of the other jig being bolted to the crankshaft flange, the respective adjusting screws contacting the flange of the hollow member and the crankshaft flange to provide for centering the member and crankshaft on the plate-like jigs.

ALFRED LOADER.
